UNITED STATES PATENT OFFICE.

ANDREW GROW, OF QUEENSVILLE, INDIANA.

FEEDER ATTACHMENT FOR CLOVER-HULLERS.

SPECIFICATION forming part of Letters Patent No. 654,624, dated July 31, 1900.

Application filed March 20, 1900. Serial No. 9,391. (No model.)

To all whom it may concern:

Be it known that I, ANDREW GROW, a citizen of the United States, residing at Queensville, in the county of Jennings and State of Indiana, have invented certain new and useful Improvements in Feeding Attachments for Clover-Hullers; and I do hereby declare the following to be a full, clear, and exact description of the invention, such as will enable others skilled in the art to which it appertains to make and use the same.

My invention relates to feeding attachments for clover-hullers or other similar machines.

15 The object of my invention is to provide an improved combination of parts whereby a simple, cheap, and compact form of feeder may be produced and in which the clover may be more completely freed or cleared from 20 the feeding-forks and guard and at the same time more uniformly fed to the hulling cylinder and chamber.

The invention consists of the construction and combination of parts substantially as 25 herein shown and described, and particularly pointed out in the annexed claim.

In the accompanying drawings, forming a part of this specification, Figure 1 is a longitudinal vertical sectional view of an embodiment 30 of my invention. Fig. 2 is a transverse sectional view taken on line xx of Fig. 1, and Fig. 3 is a detail view of the parts employed for operating the reciprocating feed-table or hopper and the supplementary guard or de- 35 pressor frame.

In the drawings like letters of reference designate corresponding parts in the several figures.

Referring to the drawings, A designates the 40 main frame of the feeder, with the hulling cylinder and chamber arranged at its left or rear end. Supported by and reciprocating on the frame is an inclined feed-table or hopper B, its front end being supported by bars C C, 45 pivoted to the hopper and to the lower part of the main frame. The rear end of the hopper rests and moves upon the platform D. A number of feed-bars E, having their rear ends somewhat widened and serrated, are secured 50 to the bottom of the hopper, with the serrated

ends extending beyond the rear end of the hopper.

Journaled in the lower part of the main frame is a crank-shaft F, having bars G G connecting its crank-arm with the bars C C, by 55 means of which upon the rotation of the shaft the hopper is reciprocated. In the upper rear part of the frame is journaled a double crank-shaft H, on which are mounted the feeding-forks I I, which operate alternately down 60 through the slats or bars of the main or stationary guiding and guard frame J, secured to standards on the main frame. The forks are held in the proper working position on the shaft by links K K, pivoted to the main 65 frame of the machine and to a short bar extending from the fork-head. A large drive or band pulley L is fixed to one end of shaft H, and on the other is a small pulley M. A small pulley N is fixed to shaft F, and a band 70 N' passes around pulleys M N, so that the rotation of shaft F is effected by the rotation of the large drive-pulley L.

Attached to or immediately in front of the main or stationary guard J and extending 75 down to the rear thereof is a supplementary movable or oscillating guard-frame O. Bars or links P are pivotally connected with the lower part of the supplementary frame and to bars G G by means of a cross-bar G', so that 80 upon the rotation of the shaft the lower part of the supplementary frame will be drawn down toward and raised from the platform D. It will thus be readily seen that at the end of the backward movement of the feed-table or hopper the supplementary frame will have about reached its lowest point and pressing or forcing the clover down in front of and between the serrated feed-bars, thereby 85 enabling them to feed a large and more uniform quantity to the hulling cylinder and chamber. The movement of the supplementary frame also clears the clover from the main guard-frame and feeding-forks, thereby 90 confining the material to the lower part of the hopper and preventing the entangling and accumulation of the same about these parts. 95

A spring Q, attached to the rear end of the hopper or feed-table, holds that end down upon the platform D.

I do not wish it understood that I limit my invention to the particular details of construction herein shown and described, as they may be changed without departing from the 5 scope of my invention.

What I claim, and desire to secure by Letters Patent, is—

In a feeding attachment for clover-hullers, the combination of the feed-table or hopper 10 B having bars E, bars C C pivotally connected with and supporting the same, crank-shaft T, links or bars G G connecting bars C C and

the crank-arm of said shaft, a movable supplementary depressor-frame O, and links or bars P P connecting the same frame and 15 crank-arm, all operating substantially as shown and described.

In testimony whereof I affix my signature in presence of two witnesses.

ANDREW GROW.
